United States Patent Office.

FISHER A. SPOFFORD AND MATTHEW G. RAFFINGTON, OF COLUMBUS, OHIO.

Letters Patent No. 95,531, dated October 5, 1869.

IMPROVEMENT IN WATER-VELOCIPEDES.

The Schedule referred to in these Letters Patent and making part of the same.

To all whom it may concern:

Be it known that we, FISHER A. SPOFFORD and MATTHEW G. RAFFINGTON, of Columbus, in the county of Franklin, and State of Ohio, have invented a new and improved Water-Velocipede; and we do hereby declare that the following is a full, clear, and exact description thereof, which will enable others skilled in the art to make and use the same, reference being had to the accompanying drawings, forming part of this specification.

Figure 1 represents a plan or top view of our improved water-velocipede.

Figure 2 is a side view, partly in section, of the same.

Similar letters of reference indicate corresponding parts.

This invention relates to a new mechanism for propelling water-craft by muscular power, and by the aid of levers, ratchet-wheels, &c., applied to paddle-wheels, as hereinafter more fully described.

A represents the body of the boat.

B is a transverse shaft hung therein.

C are the paddle-wheels, mounted on the ends of the shaft B.

On the shaft B are also mounted, ratchet-wheels *a*, as shown.

D are toothed wheels, hung loose on the shaft B, and provided with spring-pawl *b b*, which mesh into the teeth of the ratchet-wheels *a a*.

Each wheel D is hung between two ratchet-wheels, as shown, those on its opposite side having their teeth set in opposite directions.

On each side of each wheel D is also a pawl, adapted for the ratchet-wheel *a* on such side.

One set of pawls is thrown into gear with its set of ratchet-wheels, to turn the shaft B in one direction, and in order to reverse the motion of the shaft, the other pair of pawls is thrown into gear with the other pair of ratchet-wheels.

E is a transverse shaft, hung in the boat, and carrying two loose toothed segments, F F, which mesh into the teeth of the wheels D.

G is a lever, pivoted with its end to the bottom of the boat, and connected, by rods *c c*, with the segments F, respectively.

By oscillating the lever G, the segments will be oscillated in opposite directions, and will impart similar motion to the wheels D, which will revolve the shaft B, and thereby propel the boat.

The lever G is or may be connected by a rod, *d*, with another similar lever, H, which can also be operated by passengers, both levers having cross-bars *e e*, to be readily handled.

Having thus described our invention,

We claim as new, and desire to secure by Letters Patent—

A water-velocipede, consisting of the lever G, rods *c*, segments F, pinions D, pawls *b*, ratchet-wheels *a*, and paddle-shaft B, all combined and operating substantially as herein shown and described.

F. A. SPOFFORD.
